US0D1077699S

(12) **United States Design Patent** (10) **Patent No.:** **US D1,077,699 S**
(45) **Date of Patent:** **** Jun. 3, 2025**

(54) **STEERING WHEEL COVER**

(71) Applicant: **Rong Wang**, Chongqing (CN)

(72) Inventor: **Rong Wang**, Chongqing (CN)

(**) Term: **15 Years**

(21) Appl. No.: **29/987,539**

(22) Filed: **Jan. 24, 2025**

(51) **LOC (15) Cl.** **12-16**

(52) **U.S. Cl.**

USPC **D12/177**
